ROTARY DEVICES AND CASING STRUCTURES THEREFOR

Hans Robert Nilsson, Ektorp, Sweden, assignor, by mesne assignments, to Svenska Rotor Maskiner Aktiebolag, Nacka, Sweden, a corporation of Sweden

Application October 26, 1954, Serial No. 464,687

7 Claims. (Cl. 230—143)

The present invention relates to a casing structure for a rotary device of the kind providing working spaces or chambers between intermeshing rotors of the screw wheel type. Such devices may be employed as compressors to compress a gaseous fluid, or as engines generating power by the expansion of such fluid. More specifically, the invention relates to a casing structure for such a device, having at least two intersecting parallel bores for a corresponding number of parallel rotors provided with intermeshing helical lobes and grooves and mounted to rotate in said bores.

One object of the invention is to provide a casing structure permitting relative expansions of different parts of the rotary device due to temperature differences during the operation of the same without warping of the casing or derangement of the close running fit between the rotors and the bores enveloping the same.

Another object of the invention is to provide a casing structure in which only the parts thereof exposed to high temperatures or wear are made of a high resistant material such as steel and which is comparatively expensive while the rest of the casing is made of a cheaper and not so resistant material. In this respect the invention contemplates the use of a light weight material such as light metals or light metal alloys in order to reduce the total weight of the complete rotary device without affecting its performance.

A further object of the invention is to provide a casing structure having a cooling jacket providing an effective and uniform cooling.

A still further object of the invention is to provide a double-walled casing structure having a cooling jacket space between its walls, the inner one of said walls being relatively thin to promote an effective and uniform cooling of the inner and outer walls of the casing structure but yet able to withstand high pressure differences between the working chambers of the rotary device and the cooling jacket space thereof.

According to the invention the new casing structure comprises an inner lining and an outer housing supporting said lining, the inner lining comprising barrel portions formed to envelop the corresponding rotor sections and consisting of a material too thin and insufficient in strength to withstand the pressure conditions prevailing during operation of the device and the outer housing being provided to maintain the inner lining undeformed in its original shape.

Further objects and advantages of the invention will be apparent from the following description considered in connection with the accompanying drawings which form a part of this specification, and of which:

Fig. 1 is a vertical longitudinal section on the line 1—1 of Fig. 3 through a rotary compressor device provided with a casing structure constructed according to the invention.

Fig. 2 is a vertical longitudinal section on the line 2—2 of Fig. 3 of the casing structure of the device.

2

Fig. 3 is an end view of the casing structure taken in projection on the line 3—3 of Fig. 2.

Fig. 4 is a horizontal longitudinal section of the casing structure on the line 4—4 of Fig. 2.

Fig. 5 is an end view of the casing structure taken in projection on the line 5—5 of Fig. 2.

Fig. 6 is a transverse section of the casing structure on the line 6—6 of Fig. 2.

Fig. 7 is an end view taken in projection on the line 7—7 of Fig. 1 of a ring member to close the outlet ends of the rotor grooves and provided with a conduit groove for the working medium.

Fig. 8 is a horizontal longitudinal section of the ring member on the line 8—8 of Fig. 7.

Fig. 9 is a longitudinal view of one half of the ring member taken in projection on the line 9—9 of Fig. 7.

Fig. 10 is a detail section of the ring member taken on the line 10—10 of Fig. 7.

The casing structure for the compressor has an outer housing 12 comprising two principally cylindrical jacket portions 14 and 16 intersecting each other and providing two intersecting parallel bores 18 and 20 for a male and a female rotor, respectively, of which the male rotor 22 is shown in Fig. 1, said rotors being provided with intermeshing helical lobes and grooves and mounted in a manner, which will be further described below, to rotate in said bores. The bores 18, 20 are provided with internal projections consisting of annularly disposed fins 24 evenly distributed along the inside of the bores 18, 20 and so arranged that the fins in one of the bores pass over into the corresponding fins in the other bore. Said annular fins 24 serve as supporting means for a thin-walled inner lining 26 comprising two barrel portions 28 and 30, respectively, for each of the bores 18, 20 formed to envelop the corresponding rotor in its respective bore. The barrel portions 28, 30 of the lining are provided with annularly disposed external projections or fins 32 which are in engagement with the annular fins 24 on the inside wall of the bores 18, 20 of the outer housing 12. The fins 24 of the outer housing 12 are provided each with a lateral groove 34 and the fins 32 of the barrel portions 28, 30 of the lining are provided with a corresponding laterally protruding tongue portion 36 in keying engagement with the respective groove 34. These finger portions interlock each other in one and the same direction so that an axial dilatation of the inner lining 26 in relation to the outer housing 12 is permitted.

The barrel portions 28, 30 are inserted separately in respective bores 18, 20 of the housing, the top portions of its fins 24 being cut away at 38 to render the insertion possible and thereafter the barrel portions are turned so that they are brought to seat keyed by the fins 24, 32 engaging each other. When the barrel portions 28, 30 are seated one pair of the meeting edges of said barrel portions, in the illustrated device the pair 40 at the top, is welded together while the pair 42 at the bottom is left free to permit a perimetral dilatation of the barrel portions 28, 30. The centre of the bores for the lining in the outer housing is preferably displaced upwardly a fraction of a millimetre to press the lining upward and minimize its displacement downwardly.

The fins 24 of the bores 18, 20 which support the inner lining 26 define a number of annular cooling spaces 44 evenly distributed along the casing structure and unload to a high degree the inner lining from the pressure strains; the same is exposed to during the operation of the rotary device. The fins 32 of the lining 26 serve as further reinforcements for the lining wall so that the same can be made very thin but yet be able to withstand high pressure differences between the working chambers of the rotors and the cooling spaces 44 of the casing

structure. A thin wall of the lining enables an effective and uniform cooling of the inner and outer walls of the casing structure.

According to a preferred construction the housing is made of a light metal or of a light metal alloy, such as aluminum or aluminum alloy, and the lining of a wear and high temperature resistant material, such as steel, in order to obtain a light but nevertheless stable casing construction.

The illustrated rotary device has a principally axial inlet 46 for the working medium which opens into an inlet chamber 48 provided at one end 50 of the outer housing 12. Said inlet chamber 48 is in part, at 52, located in the end 50 referred to of the housing 12 and in part, at 54, in an end wall 56 fastened to said end 50 of the housing 12. The ends 58 of the rotors exposed to the inlet 46 are in part covered by means of a shielding plate 60 to prevent a direct communication between the inlet and outlet ducts of the device through any of the grooves of the rotors. For that reason the shielding plate 60 is arranged at the upper half of the intersection 62 between the rotor ends and properly displaced in relation to the direction of rotation of the respective rotor.

The inlet chamber 48 surrounds the inlet ends 58 of the rotors annularly and is provided at its top with an inlet connecting piece 64.

The outlet 66 of the rotary device is radial and located at the top of the casing structure toward the opposite end thereof in relation to the inlet end 46. The outer housing has an opening 68 and the inner lining 26 an opening 70 for said inlet 66 which outwardly ends in a connection piece 72.

The top portion 74 of the outer housing diverges from the generally cylindrical form it has in its other portions and is raised radially upwardly, said top portion 74 being provided with inside longitudinal reinforcing fins 76. As mentioned above, the inner annular fins 24 of the outer housing are cut off at 38 and in order to carry the top intersecting portions 78 (Fig. 6) of the barrels 28, 30 and prevent the corresponding part of the lining 26 becoming downwardly displaced, this part of the lining is provided with upwardly extending lugs 80 and the top portion 74 of the outer housing with a downwardly extending lug 82. A stud 84 is inserted through the lugs to join them together.

To the ends of the rotors, shaft portions 86, 88 are bolted by means of which the rotors are supported in hub portions 90, 92 of steel or other high temperature and wear resistant material. Said hub portions enclose suitable bearing and sealing arrangements which, however, form no part of the invention and therefore are not shown in detail.

The hub portions 90 for the rotor shafts 86 at the inlet end are supported in seats 94 provided in the outer housing itself, said seats being strengthened by radial fins 96 extending as spokes across the annular inlet to the corresponding ends of the rotors. The surfaces 98 of the outer housing fitting closely with the hub portions 90 are provided with a lining 100 of steel or other high temperature and wear resistant material to protect said surfaces from wear of the assembled parts.

At the outlet end, the rotors end approximately in a plane flush with the vertical transverse section through the centre of the outlet 66. The hub portions 92 for the rotor shafts 88 at the outlet end are carried by an internal flange 102 provided on an extension member 104 of the outer housing formed as a sleeve and bolted to the end 106 of the outer housing. The surface 108 of the flange 102 fitting closely with the hub portion 92 is provided with a similar protection lining 110 as the lining 100 for the inlet hub portion 90.

The housing extension member 104 is closed at its outer end by a lid 112 through the centre of which is inserted an inlet 114 for a cooling medium to each rotor. The rotors and their shafts are hollow to form a central

cooling channel 116 closed at the outer end 118 of the shafts 86 at the inlet end and divided by means of a partition wall 120 in two halves 122, 124. A pipe 126 conducts the cooling medium from its inlet 114 to the channel half 122 most remote from said inlet 114. A number of radially distributed channels 128 in the bodies of the rotors conduct the cooling medium back to the channel half 124 most nearly adjacent to the cooling medium inlet 114 from which channel half the cooling medium is discharged through outlets 130.

The male and female rotors are provided with synchronizing gears 132 located at the ends of the rotor shafts 88 and the rotor shaft 86 of the male rotor is provided with a connection piece 134 for its attachment to a prime mover (not shown).

In order to close the grooves of the rotors at their outlet ends a ring member 136 is provided which is welded to a sleeve 138 guided by the inner lining 26 of the casing structure. The closing ring member 136 comprises two principally annular half portions 140, 142 concentrically arranged around respective rotor shafts 88 and the ends of said half portions 140, 142 which face each other pass over into chord bars 144 which are riveted together. The closing ring member 136 is provided at its top with a conduit groove portion or funnel 146 for the working medium which faces a circumferentially restricted portion of the outlet ends of the rotors and communicates with the outlet duct 66 of the rotary device.

The sleeve 138 attached to the closing ring member 136 consists of two barrel halves 148, 150 conformable to the barrel portions 28, 30 constituting the inner lining 26. The free end of the sleeve 138 is provided with offset fin portions 152, 154 keyed into seats 156, 158 in the confronting ends of the lining 26 and the housing extension member 104. This arrangement effectively holds the outlet funnel 146 in position and prevents the deformation of the composite structure of closing ring 136 and sleeve 138 at its top.

A number of evenly distributed distance bolts 160 connect the closing ring member 136 with the internal flange 102 of the housing extension member 104 to further stabilize the construction.

The outer housing 12 is provided with a base 162 and a number of annularly and longitudinally disposed external fins 164 and 166, respectively, to further reinforce the housing 12 and to improve the heat transfer to the atmosphere.

The invention also comprises any rotary device of the type referred to provided with a casing structure as set forth.

What is claimed is:

1. A housing structure for rotary devices of the kind having at least two intermeshing rotors with cylindrical envelopes and parallel axes, comprising an inner casing member having a wall providing cylindrical intersecting barrel portions with bores and axes corresponding with the envelopes and axes of the respective rotors, and an outer casing member around said inner casing member and encompassing the latter symmetrically thereto, each two of said intersecting barrel portions of said inner casing having one pair of their longitudinal edges fastened together while the other pair remains free in order to allow expansion of said barrel portions in a circumferential direction, and at least one member of said inner casing and outer casing members being provided with interengaging tongue and groove arrangements having necessary axial clearance in the grooves to provide for the support of the inner casing member in the outer casing member while allowing axial expansion therebetween.

2. A housing structure as claimed in claim 1, in which the inner casing member and the outer casing member are each provided with axially spaced projections in the form of annular disposed ribs provided with axially dis-

posed slit and tongue means providing said tongue and groove arrangements for interengagement therebetween in one and the same direction so as to allow said axial expansion of the inner casing member relative to the outer casing member.

3. A housing structure as claimed in claim 1, in which the inner casing member is provided with radially outwardly, and the outer casing member with radially inwardly, directed lugs overlapping one another and pinned together.

4. A housing structure as claimed in claim 2, in which the annular ribs of the outer casing member comprise arcuate lengths of less circumferential width than the circumferential width of the barrel portions of the inner casing member in order to allow the introduction of said barrel portions and turning of the latter into slit and tongue engagement with the outer casing member.

5. A helical screw device operating with a gaseous medium and comprising a housing structure having an inlet and an outlet opening disposed adjacent opposite ends, a set of at least two intermeshing rotors with cylindrical envelopes and parallel axes rotatably mounted in said housing structure, said housing structure comprising an inner casing member enveloping said set of rotors and an outer casing member around said inner casing member and encompassing the latter symmetrically thereto, the opening adjacent to the high pressure end being defined by principally radially directed duct means, in a vertical transverse plane to which the corresponding ends of the rotors terminate in flush, and a composite ring element facing said ends of the rotor and including a circumferentially major portion closing said ends of the rotors and a circumferentially restricted minor por-

tion providing a conduit groove for the operating medium and communicating with said radially directed duct means.

5. A helical screw device as claimed in claim 5, in which said composite ring element is carried by a composite sleeve structure inserted into and supported by said inner casing member.

10 7. A helical screw device as claimed in claim 6, in which the ends of said composite sleeve structure remote from said composite ring element is provided with axially disposed fin members and the inner and outer casing members with corresponding slit means to receive said fin members.
